UNITED STATES PATENT OFFICE.

ISAAC E. PALMER, OF MIDDLETOWN, CONNECTICUT.

RUNNING-GEAR FOR VEHICLES.

No. 889,960.

Specification of Letters Patent.

Patented June 9, 1908.

Application filed November 20, 1907. Serial No. 402,954.

To all whom it may concern:

Be it known that I, ISAAC E. PALMER, a citizen of the United States, and resident of Middletown, in the county of Middlesex and 5 State of Connecticut, have invented a new and useful Running-Gear for Vehicles, of which the following is a specification.

My invention relates to running gear for vehicles and more particularly to running 10 gear for automobiles where the wheels are, one or more sets of them, arranged out of transverse alinement for the purpose of relieving the throw of the body of the vehicle in passing over obstructions on the road.

15 The object of the invention is to provide for swinging a driving wheel preferably simultaneously with the swinging of the forward or leading wheels to compensate for the lateral drag on a wheel in turning a corner and 20 at the same time keep the driving gear which operates the drive wheel in practical operative relation to the driving shaft.

In the accompanying drawings, Figure 1 is 25 a top plan view of so much of the running gear as will suffice to show the relation of the several parts to one another when assembled for use, Fig. 2 is an enlarged vertical section in the plane of the line A—A of Fig. 1, Fig. 3 is a horizontal section in the plane of the line 30 B—B of Fig. 2, Fig. 4 is a top plan view similar to Fig. 1, showing a modified arrangement of driving mechanism, Fig. 5 is an enlarged vertical section in the plane of the line C—C of Fig. 4, Fig. 6 is a vertical section in the plane of the line D—D of Fig. 5, 35 Fig. 7 is a section in the plane of the line E—E of Fig. 5, Fig. 8 is a view in detail partly in plan and partly in section of a portion of the interlocking teeth for connecting the sprocket, 40 shown in Fig. 5 with the traction wheel, Fig. 9 is a view corresponding to Fig. 5, showing a modified form of connection between the driving sprocket wheel and the traction wheel, Fig. 10 is a section of the same in the 45 plane of the line F—F of Fig. 9, Fig. 11 is a sectional view in detail showing the interlocking of the teeth for connecting the sprocket wheel with the traction wheel, Fig. 12 is a view similar to Figs. 5 and 9 showing 50 another modified form of connecting the sprocket drive wheel with the traction wheel, and Fig. 13 is a section of the same in the plane of the line G—G of Fig. 12.

The frame of the running gear is denoted 55 by 1 and may be of any well known or approved form. The front axle is denoted by 2

and the rear axle by 3. The front axle is set in a plane oblique to the longitudinal axis of the running gear so as to place the front wheels 4 and 5 out of transverse alinement, 60 the wheel 4, in the present instance, taking the lead of the wheel 5 as the vehicle advances. These wheels 4 and 5 may be secured to the axle 2 in any well known or approved manner for causing them to be simultaneously tilted for purposes of steering. 65

In the present instance, the steering wheel, not shown, may connect by means of a rod 5* with suitable gear for operating the angle lever 6 secured to the hub at 7 for tilting the 70 wheel 4 and one arm of the angle lever 6 may be connected by a rod 8 with an arm of the angle lever 9 connected with the hub of the wheel 5 at 10 for swinging the wheel 5. The arm of angle lever 9, connected with angle 75 lever 6, is somewhat longer than the corresponding arm of angle lever 6, to compensate for the lead of the wheel 4.

The rod 5* may be connected by means of a rod 11 with a tilting arm 43 on the hub of a 80 rear wheel as will be hereinafter more particularly described. In the present instance, the rear axle 3 is fixed and the rear wheels 18, 19, are mounted, the one 18 to rotate with the part 14 of a divided axle, as is usual, and 85 the other 19 hinged to the end of the shaft 3 to be swung slightly toward and away from the longitudinal axis of the running gear and driven by the other part 13 of the divided axle through a system of gear wheels 15, 16 90 and 22.

The gear 15 is set upon a stud axle 17 made fast to the gear frame and intermeshed with the gears 22 and 16, the former fixed to rotate with the axle 13 and the other 16 fixed 95 to rotate with the wheel 19.

The teeth on the wheel 16 are made slightly convex and somewhat longer than the teeth on the wheel 15, the teeth on the wheel 15 being preferably made slightly concave so 100 that the wheel 19 may swing on its hinge connection with the axle 3 inwardly without disarranging the connection between the gears 15, 16.

The spindle 27 is fixed to or may be a part 105 of a vertical spindle head 28, the latter being secured between the arms 29, 30, of a yoke made integral with or secured to the end of the axle 3 and the arrangement is such that the tilt of the wheel 19 through the arm 43 110 and rod 11 shall be just sufficient to compensate for the lateral drag on the wheel 18 when

the car goes around a corner or swerves from a straight course.

In Fig. 4, the dividing shaft 20, mounted in suitable bearings in the frame 1, illustrates a 5 drive shaft of any well known or approved form carrying sprocket wheels 21, 22, connected by sprocket chains 23, 24, respectively, with the sprocket wheels 15*, 16*, on the rear traction wheel hubs.

10 Referring now to Figs. 5 to 8 inclusive; the traction wheel hub is made in several parts, one part 25 being fixedly secured in the present instance to the wheel 19, as the bolts 26, the wheel itself being mounted to 15 rotate on the axle spindle 27.

The spindle head 28 is held in position by a hinge pintle 32 extending through the ends of the arms 29, 30, and through the head 28, and locked in position by a cross pin 33. 20 The free ends of the arms 29 and 30 of the yoke are extended laterally, as clearly shown in Fig. 6, and their outer faces rounded conveniently in the arc of a circle to receive a bearing ring 34 which is made fast thereon 25 in any suitable manner.

On the ring bearing 34 a hub section 35 is mounted to rotate freely and is provided with sprocket teeth, the teeth and the hub section 35 forming together the sprocket 30 wheel 16 hereinbefore referred to. This hub section 35 is extended to form a bearing 36 for the brake band not shown but which may be of any well known or approved form and the said hub section 35 is further extended 35 toward the traction wheel at intervals to form projecting lugs 37 within which there is fixed a ring 38, in the present instance by means of screws 39* which extend through the lugs 37 into the ring, the said ring 38 being provided at intervals, in the present instance at diametrically opposite points, with recesses 39, 40, in which teeth 41, 42, projecting from the face of the hub section 25, as clearly shown in Fig. 8, enter to interlock 40 the sprocket wheel 35 with the hub section 45 25 through the intervening connecting ring 38.

As the axle 3 is fixed, the bearing ring 34 fixed on the arms 29, 30, of the axle, will remain fixed and the sprocket wheel mounted 50 on the ring 34 will maintain its relation to the axle whatever the swinging position of the traction wheel 19 may be as it swings on the hinge pintle 32.

As the traction wheel 19 swings on the 55 hinge pintle 32 and at the same time rotates together with the sprocket wheel and interconnecting ring 38, the teeth 41, 42, will gradually withdraw from the bottom of the recess 31 and then gradually approach the 60 bottom of said recess, one of said teeth being at its innermost position at the same moment that the diametrically opposite tooth is in its farthest withdrawn position but at all times the interlocking of the parts will remain secure in any tilting position which the

traction wheel is made to assume and this without in any manner interfering with the constant relation of the sprocket wheel to its driving mechanism.

The arm for swinging the traction wheel 19 70 is denoted by 43 and extends forwardly and inwardly from the pintle head 28 with which it may be formed integral if so desired. The connecting rod 11 connects with the end of this arm 43.

The connection hereinabove described is such that when the leading wheels 4 and 5 are swung into the positions shown in dotted lines, Fig. 4, the rod 11 will be pushed back thereby swinging the traction wheel 19 into 80 the position shown in dotted lines, Figs. 1 and 4. This arrangement admits of not only arranging the traction wheels out of transverse alinement but further admits of swinging 85 a wheel simultaneously with the swinging of the leading wheels to prevent the wheels from scraping laterally along the surface of the ground and so endangering the integrity of the tires.

In Figs. 9, 10 and 11, I have shown the 90 sprocket wheel hub section 47 provided with an annular series of recesses 48 which receive consecutive teeth 49 of an annular gear fixed to the traction wheel 19 instead of the two teeth diametrically arranged as in the Figs. 5 95 to 8 inclusive and the interconnecting ring 38 is omitted, a keeper ring 50 being made fast to the arms of the yoke to hold the hub section 47 in position on its seat.

In Figs. 12 and 13, the hub 51 is fixed directly to the traction wheel 19 and is provided on its outer face with an annular convex surface 52 in which are formed grooves 53 extending lengthwise of the hub and at suitable intervals apart around the convex 105 annular portion of the hub, in the present instance at intervals of one-sixth of the circumference. The sprocket wheel 54 is seated on this convex annular portion of the hub and is locked against a rotative movement with respect to the hub by means of screws 55, 56, extending through the base of the sprocket wheel and projecting into the groove 53 while at the same time the hub 51 is permitted a rocking or wabbling movement with respect to the sprocket wheel 110 when the wheel 19 is swung as in changing the direction. In this form, the wheel spindle 57 is provided with the yoke 58 and the socket 59 for receiving the hinge pintle 32 is 115 formed integral with the axle.

What I claim is:

1. In running gear for vehicles in which the members of a pair of wheels to the rear of a pair of steering wheels are arranged out of 125 transverse alinement, means for swinging a rear wheel out of its normal plane to compensate for lateral drag in turning a curve.

2. In running gear for vehicles, a pair of steering wheels, a pair of supporting wheels 130

to the rear of the steering wheels, the members of said supporting wheels being arranged out of transverse alinement and one of said wheels being mounted to swing toward and away from the longitudinal central axis of the running gear, and means connected with said swinging wheel and with the steering wheels whereby the said wheel is swung simultaneously with the swinging 10 of the steering wheels and in the opposite direction to compensate for lateral drag.

3. In running gear for vehicles, the combination with a forward fixed axle and wheels hinged to the axle to swing toward 15 and away from the longitudinal axis of the running gear, of axles to the rear of said fixed axle, a drive wheel pivoted to one of said axles to swing toward and away from the longitudinal axis of the running gear, and 20 means for simultaneously swinging the wheels on the two axles.

4. In running gear for vehicles, the combination with a fixed axle and a driving wheel hinged to the said axle to swing toward and away from the longitudinal axis of the running gear, of a driving gear having a laterally variable interlocking engagement with the drive wheel whereby the driving gear may be maintained in the same plane 25 during the tilting movement of the drive wheel without disengaging the driving gear from the drive wheel.

5. In running gear for vehicles, the combination with a fixed axle and a drive wheel 30 hinged to the axle to swing toward and away

from the longitudinal axis of the running gear, of a driving gear wheel rotatably supported on the swinging gear frame in proximity to the drive wheel, the said gear wheel and the drive wheel being provided, the one 40 with concave teeth and the other with convex teeth for engaging the said concave teeth for effecting a laterally variable interlocking engagement between the driving gear and the drive wheel. 45

6. In running gear for vehicles, the combination with a driving axle with wheel thereon and a fixed axle with wheel thereon arranged to swing, of a driving gear wheel on the driving axle, an intermediate gear 50 engaged with said driving gear and a gear on the said swinging wheel engaged with said intermediate gear.

7. In running gear for vehicles in which the members of a pair of wheels are arranged 55 out of transverse alinement and mounted to swing toward and away from the longitudinal axis of the running gear, means for simultaneously tilting the two wheels at different angles to the longitudinal axis of the running gear. 60

In testimony, that I claim the foregoing as my invention, I have signed my name in presence of two witnesses, this 12th day of November A. D. 1907.

ISAAC E. PALMER.
